UNITED STATES PATENT OFFICE.

ALBERT N. PETTENGILL, OF ILION, NEW YORK.

FISHING-REEL.

SPECIFICATION forming part of Letters Patent No. 361,890, dated April 26, 1887.

Application filed August 3, 1885. Serial No. 173,435. (No model.)

To all whom it may concern:

Be it known that I, ALBERT N. PETTENGILL, a citizen of the United States, residing at Ilion, in the county of Herkimer and State 5 of New York, have invented certain new and useful Improvements in Reels for Fishing-Rods; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a perspective view of the blank from which the guard is formed. Fig. 2 is a perspective of the reel guard or band. Fig. 3 is a perspective of the reel-band cut into open-work. Fig. 4 is a 20 transverse sectional view of the reel. Fig. 5 is an inverted plan view with the central plate, C, broken away.

25 My invention relates to fishing-reels; and it consists in the construction and novel combination of parts, as will be hereinafter fully described, and particularly pointed out in the claim.

30 Referring by letter to the accompanying drawings, A designates a circular blank or disk of sheet-brass, from which the reel guard or band B is cupped or drawn up in one solid piece, and is afterward cut out into an open-work band to lighten the structure. A center plate, C, is left and is supported by integral radial arms D, connecting the band B and center plate, C. The center plate, C, is provided on its inner face with an arched flat spring, E, one end of which is secured to a headed stud, F, and bears outwardly against 35 a stud or stop-pin, G. The other end of the spring E engages the outer flat edge of a triangular-shaped pivoted detent, H. The stop-pin G holds the spring E in engagement with the pivoted detent H.

40 45 The reel-cylinder I is provided on the inner end of its hub J with an integral spur-gear or pinion-wheel, K, the teeth of which engage the triangular-shaped detent H. The curved

spring E holds the triangular-shaped detent H in engagement with the teeth of the pinion. 50 The triangular-shaped detent permits the reel-cylinder I to be turned in either direction, a handle, L, being provided by which to turn it.

The reel guard or band B and the plate C 55 are respectively provided with a screw-hole, M, and a pin-hole, N, for the reception of the securing-screw O and the stop-pin P on the attaching-plate Q. The stop-pin P is employed to prevent the plate Q from being accidentally turned aside, and also to facilitate the ready adjustment of said plate to place in changing the reel from a side reel to a top reel. A second attaching-plate, R, is provided and is secured to the center plate, C, by 60 the journal S, on which reel-cylinder I revolves, and a nut, T. This attaching-plate R is provided with a stop-pin, P, which prevents said attaching-plate from turning on its securing screw or journal S.

70 Either of the attaching-plates can be removed when desired, and by the removal of the one or the other of them the reel can be converted into a top reel or a side reel, and vice versa, so that the reel is adapted to suit 75 the tastes of fishermen desiring either a side reel or a top reel.

Having thus fully described this invention, what I claim, and desire to secure by Letters Patent, is—

80 The combination, with the reel-band constructed of a single piece of material and having the center plate, C, of the triangular-shaped detent H, pivoted to the center plate, C, the spring E, secured to the stud F, fixed 85 in the center plate, the stop-pin G, engaging the spring E, and detachable plate secured in place by a screw and engaging a stop-pin, P, substantially as specified.

90 In testimony whereof I affix my signature in presence of two witnesses.

ALBERT N. PETTENGILL.

Witnesses:

PETER HARTER,

AUGUST T. KELLNER.
